UNITED STATES PATENT OFFICE.

ROBERT L. WERNZ, OF FREEPORT, ILLINOIS.

AUTOMOBILE-SIGNAL.

1,275,114.

Specification of Letters Patent. Patented Aug. 6, 1918.

Application filed September 5, 1917. Serial No. 139,823.

To all whom it may concern:

Be it known that I, ROBERT L. WERNZ, a citizen of the United States, residing at Freeport, in the county of Stephenson and State of Illinois, have invented new and useful Improvements in Automobile-Signals, of which the following is a specification.

This invention relates to signals, and more especially to those intended primarily for use on an automobile to permit the driver to indicate whether he intends to turn to the right or left or to stop.

The invention contemplates the use of two indexes or arrows pivotally mounted and capable of movement independently into horizontal or vertical positions, with which are associated electric lamps automatically illuminated at night so that the relative positions and colors of the lamps will indicate the driver's intentions the same as the arrows which of course can then not be seen.

The invention consists in mechanical and electrical details of structure for swinging the arrows and for locking them in certain positions, and making and breaking the circuits to the lamps, all as hereinafter more fully described and claimed and as shown in the drawings wherein—

Figure 1 is a front elevation of this signal with the face plate partly broken away.

Figs. 2 and 3 are sections on the lines 2—2 and 3—3 respectively of Fig. 1.

Fig. 4 is a diagram illustrating the wiring.

Within a casing 1 of appropriate size and shape and properly mounted on the rear of the car are three red lamps 2, 3 and 4 and centrally between the two uppermost lamps 2 and 3, a white lamp 5, all being bulbs as seen in Fig. 2, preferably mounted in sockets carried within the rear wall of the casing. The front of the latter is glass as shown at 6, and forward of the white lamp 5 the casing may carry a numbered plate 7 which this lamp illuminates at night when it burns constantly. The lower portion of the casing carries a metal partition 8 standing well behind the glass and hiding most of the mechanism, and this partition may carry a lens 9 forward of the lower lamp. The red lamps are disposed in a triangle, and herein-after I will speak of that numbered 2 as the left lamp and that numbered 3 as the right

lamp since they are placed relatively at the left and right sides of the car and respectively adjacent the left and right arrows, and the remaining red lamp 4 stands considerably below the line of the other two and at a point mid-way between them while the white lamp 5 may have any appropriate position, but is herein shown standing above the lower lamp.

The lamps are lighted from a suitable source of electricity such as a battery 10. From the same a wire 11 leads through a switch 12 to one side of all the lamps, and the switch is opened in the day time to extinguish them. A wire 13 leads from the other side of the battery directly to white lamp which therefore burns constantly when the switch is closed. A wire 14 leading from the wire 13 has branches 15 and 16 each leading through circuit closers yet to be described, and then onward as at 17 and 18 to the lamps 2 and 3 respectively. A wire 19 leads from the lower lamp 4 to another circuit closer also yet to be described in detail.

The numerals 22 and 23 designate indexes or arrows each pivoted at 21 near its rear end within the casing and carrying near its pivot a lateral arm 24 having a weight 25 so disposed that the normal tendency of the arrow is to stand oblique as indicated by the dotted line in Fig. 1. For each arrow a long lever 26 is pivoted at its lower end within the casing, while its upper end is connected by a link 27 with the arm 24, so that as the armature-lever is swung from side to side over its pivot the arrow is swung from a vertical to a horizontal position, and when vertical it is mostly hidden behind the partition 8, whereas when horizontal it is wholly exposed above the partition and is conspicuous because I will doubtless paint it white whereas the casing and partition will be painted black. The obvious intent is that when the left arrow is raised to a horizontal position as shown in the drawings, it indicates that the driver is about to turn to the left, raising of the right arrow would indicate that he is about to turn to the right, raising of neither would indicate the intention to proceed straight forward, and raising of both would indicate that he is about to slow down or stop. Such would be the signal in the day time, when the ar-

rows can be seen. They have the same movement after dark when they are not visible, and at this time the driver will close the switch 12 so that the lamp signals come into action by reason of the fact that the circuit closers are actuated by the armatures.

The numbers 32 and 33 designate electromagnets disposed in alignment with each other and standing respectively near the left and right hand sides of the casing, and I will hereinafter refer to them as the left and the right magnets; and between them stands a third electromagnet 31 hereinafter called the intermediate magnet. The left hand lever 26 moves between and carries an armature 26 for the left magnet 32 and the intermediate magnet 31, whereas the right hand lever carries an armature for the right magnet 33 and the other end of the intermediate magnet 31. Pivoted at 34 within the casing is a latch 35 for each lever, the same having a hook 36 at its free end normally raised by a weight 37 so as to come automatically into engagement with a pin 38 on the lever when the latter is swung inward as seen at the right of Fig. 1, but as seen in Fig. 2, the pendant arm 39 which carries the weight stands adjacent to the core of the magnet so that when the latter is energized the latch is tripped to disengage its hook from the pin and then the lever is swung toward the magnet. The function of the latch is to hold the lever and therefore the arrow against swinging under the vibration of the car as it travels over the roadway. Moreover, the angular position of the arrow and its weighted arm with respect to its pivot gives the same a constant tendency to swing to the position dotted in Fig. 1; and this tendency is resisted by the latch. Therefore when the latter is tripped, as just described, the lever swings part way toward the outer magnet under the influence of the weight and the armature 45 comes within its magnetic field as has been suggested. On the other hand, when an arrow drops from its horizontal position as seen at the left of Fig. 1, its weight creates the same tendency of the lever to swing toward the intermediate magnet and the armature comes into the magnetic field thereof. The latches are purposely disposed to hold the arrows in pendant position as when the driver is proceeding straight ahead, and the circuit closers next to be described are purposely arranged so that they supply no current to the lamps 2 and 3 at this time, but the lamp 4 is lighted and the signal is set at "clear", meaning straight ahead.

60 The left circuit closer is a spring tongue 45 supported at its lower end on an insulated block 44 and connected with the branch wire 15, its upper end lying normally in contact with a pin 47 which is con-

nected with the wire 17. The right circuit closer is a similar tongue 46 connected with the branch wire 16 and resting normally against a pin 48 connected with the right wire 18. The intermediate circuit closer is a tongue 49 mounted on the insulated block 70 44 which carries the left circuit closer and connected at its lower end with the wire 19 to the lower lamp 4, and this tongue is never in contact with the tongue 45 by reason of the interposed insulation shown at 43 in Fig. 4, although the tongue 49 is moved when the tongue 45 is moved. The tongues 45 and 46 are bent inward by projections 42 on the levers 26, and when the latter swing inward the circuit closers are opened. Pins 80 40 and 41 are disposed between the circuit closers and connected by a wire 20, and when both circuit closer tongues 46 are swung inward (or in other words, when both arrows stand pendant) the circuit to the lamp 85 4 is completed along the wire 19, tongue 49, wire 20, tongue 46, and branch 16, as will be clearly understood; therefore this lamp burns only when both lamps 2 and 3 are extinguished. 90

The mechanical details thus far described are amply illustrated in the drawings, but the means for energizing the electromagnets are shown only in diagram in Fig. 4. In the following description thereof I refer to 95 the circuit closers for the magnet circuit as push buttons, and if the same are actually employed they will doubtless be assembled in a plate convenient to the operator's position and the buttons labeled or lettered in 100 some way. However, it is quite possible to adopt some of the well-known systems now in use for employing circuit closers in connection with the right and left hand magnets which are actuated by the turning of 105 the steering wheel, so that the signals will be set automatically in a manner well understood and not necessary to amplify. From a suitable source of electricity such as a battery 50 a wire 51 leads to one end 110 of such magnet, and from the other side of the battery a wire 52 leads to one side of a series of circuit closers or buttons herein lettered R, N, L and S. These letters may be the initials of words meaning right, 115 neither, left, and stop, and the circuit closers may be switches, push buttons, or any appropriate devices. From the other side of the button R a wire 53 leads to the other end of the right magnet 33, the other side 120 of the button N is connected by a wire 54 with the intermediate magnet 31 and the other side of the button L is connected by a wire 55 with the left magnet 32. A wire 56 leads from a contact at the other side of 125 the button S to a point 58 where it connects with the wire 53, and another wire leads from a second contact to a point 57

where it connects with the wire 55, and through these contacts and wires the button S is branched to both the right and left hand magnets.

5 With this construction of parts, when the driver presses the button R, the right magnet 33 is energized, the right latch 35 is tripped and then the right hand lever 26 moved, and the right arrow 23 will be raised 10 to a horizontal position, where it will remain as long as this button or circuit closer R is pressed or is closed in any way. Pressure on the button L will raise the left arrow, pressure on the button S will raise both 15 arrows simultaneously, and pressure on the button N will energize the intermediate magnet. Then whichever arrow has been released by the deenergization of its respective magnet and has dropped, will be drawn 20 down to a vertical position because the armature or lever will be attracted by this intermediate magnet 31, and when the lever reaches a vertical position the latch engages the pin in a manner above described. There- 25 25 after both arrows are pendant and the signal is quite "clear," and no pressure is needed on any button to cause it to remain so. This description covers what takes place mechanically, but it is clear also that the pro- 30 jections 42 open said circuit closers whenever the levers swing inward. Therefore, when at night the operator closes the switch 12 and energizes the lamp circuit, the movement of the levers will, through their pro- 35 jections 42, open and close the circuit closers 45, 49 and 46 in a manner above described, and the result will be that the lamps now become visible when lighted whereas the arrows may be no longer seen. With the 40 parts standing in the position shown in the drawings, the left light would be illuminated red and the uppermost white light burns at all times, if both arrows were raised both red lamps 2 and 3 would be illuminated, and 45 if both arrows were dropped there would be shown a red light 4 below a white light 5. Therefore the relative position and colors of the lights constitute the signal.

What I claim is:

50 1. In a signal of the class described, the combination with three alined and spaced electromagnets, two armature levers pivotally mounted for movement in the respective spaces between the magnets, and means for energizing the latter selectively; of two signals pivotally supported for swinging movement, and links connecting the free ends of said levers with the respective signals.

60 2. In a signal of the class described, the combination with three alined and spaced electromagnets, two armature levers pivotally mounted for movement in the respective spaces between the magnets, and means for energizing the latter selectively; of two sig-

nals, each mounted near one end on a pivot 65 and having an arm projecting laterally from such end and weighted whereby the tendency is for the signal to stand normally oblique, and a link connecting said arm with the free end of one of the levers, substan- 70 tially as and for the purpose described.

3. In a signal of the class described, the combination with three alined and spaced electromagnets, two armature levers pivotally mounted for movement in the respective 75 spaces between the magnets, and means for energizing the latter selectively; of two pivoted signals, a weight on each causing it to stand normally oblique, connections between the signal and the free end of one of said 80 levers, a pin on the latter, and a pivoted latch for engaging the pin when the lever stands in one extreme position, the latch having a gravity arm standing in the magnetic field of one magnet, for the purpose set 85 forth.

4. In a signal of the type described, the combination with alined and spaced electromagnets, a lever swinging between them and serving as the armature of either, and means 90 for selectively energizing the magnets; of the signal proper, connections between it and the free end of the lever, a catch on the latter, and an angular latch pivotally supported at its angle and having a hook on one 95 arm for engaging said catch when the lever is in one extreme position and its other arm hanging in the magnetic field of one of said magnets, for the purpose set forth.

5. In an automobile signal of the type de- 100 scribed, the combination with a casing, left, right, and intermediate electromagnets mounted therein and spaced from each other, means for energizing them selectively, and two levers whereof each is pivoted at its 105 lower end within the casing for swinging movement between the intermediate magnet and one of the other magnets; of two arrow-shaped signals pivoted near their rear ends within the casing above the magnets and 110 adapted to swing to horizontal or vertical positions, connections between each arrow and the free end of one lever whereby the latter moves from within the magnetic field of one magnet into that of the other as the 115 arrow moves from one of its extreme positions to the other and travels across the neutral space between said fields by the inertia of parts, latch mechanism for holding the lever adjacent the intermediate magnet, and 120 means for tripping said latch when the other magnet is energized.

6. In a signal of the class described, the combination with a member pivoted to swing from horizontal to vertical positions and 125 weighted to stand normally between such extremes of movement, a lever pivoted at one end and connected at its other end with

41
said member and swung therewith, an armature on the lever, spaced electromagnets between which the lever swings, and means for energizing them selectively; of a signal, 5 a source of electric energy, a circuit including the source and the signal and setting the latter when it is closed, a normally closed circuit closer within said circuit, and means on the lever for opening said closer when the 10 lever is moved to one extreme position.

7. In a signal of the class described, the combination with a member pivoted to swing from horizontal to vertical positions and

weighted to stand normally between such extremes of movement, a pivoted lever connected with said member and swung therewith, an armature on the lever, spaced electromagnets between which the lever swings, and means for energizing them selectively; of a signal lamp, a circuit closer, a circuit 20 including the lamp and circuit closer and a source of energy, and a pin on said lever opening the circuit closer when the lever swings to one extreme of its movement.

In testimony whereof I affix my signature. 25
ROBERT L. WERTZ.
